UNITED STATES PATENT OFFICE

NATHANIEL E. LOOMIS AND MERLE R. MEACHAM, OF ELIZABETH, NEW JERSEY, ASSIGNEES TO STANDARD OIL DEVELOPMENT COMPANY, A CORPORATION OF DELAWARE

PROCESS AND APPARATUS FOR CRACKING HYDROCARBONS

Application filed July 22, 1925. Serial No. 45,194.

This invention relates to improvements in processes and apparatus for the cracking of hydrocarbons into lower boiling products. The invention will be fully understood from the following description, taken in connection with the accompanying drawings, in which

Fig. 1 is a diagrammatic elevation of one suitable form of apparatus; and
10 Fig. 2 is a partial plan view of the same, showing the arrangement of the digesting chambers or soaking drums.

In the present invention a very flexible system is provided, by means of which stocks 15 of varying grades may be treated under the conditions best suited for high yields of low boiling products from each stock. The apparatus will first be described and then its utilization will be particularly pointed out 20 in connection with the treatment of typical feed stocks.

Referring to the drawings, reference numeral 1 denotes a shell still or equivalent distillation or vapor-separating means, arranged in a furnace setting 2. The still 1 is preferably provided with internal horizontal flues 3, through which hot combustion gases from the furnace pass to a stack 3'. The still is connected through line 4 with condensing and fractionating equipment, such as a bubble tower 5. This tower has the usual plates 6, receiving pan 7, vapor heat exchanger 8, vapor line 9, and condenser 10. The lower portion of the tower constitutes 35 a chamber 5' for accumulation of residuum and condensate, and for other purposes.

A condensate draw-off line 11, having a valve 12, leads from the pan 7 to the still 1. A line 11a, leading to storage, the cracking coil, or other suitable equipment, is also connected with line 11. A line 11b is provided for the purpose of passing the condensate to the cracking coil. Valves 11' and 11'' control the flow through these lines. Another draw-off line 13 is arranged to receive oil from the bottom of the tower 5 and convey it through branch line 14 to the pump or pumps 15 which forward the oil through line 15' to the cracking coil 16 and digesting chambers 17, 18. An accumulator 13a may be

connected to line 13 and pipes (not shown) may convey the oil from the accumulator to pumps 15.

Alternatively, the oil from the bottom of tower 5 may be drawn off through line 13 and branch pipe 19 to a cooler (not shown) or other suitable means. A valve 20 is installed in line 13 between the branches 14 and 19. A by-pass 21, having a valve 22, connects branch line 14 with the outlet pipe 23 from the bottom of the still 1. A valve 22' is installed in line 23 and a valve 22" in line 14 below the by-pass 21. Line 23 discharges liquid oil from the still through the by-pass 23a into a tar heat exchanger 24, or directly into line 14, in accordance with the regulation of valves 22' and 23'. A line 25 serves for the withdrawal of tar from the exchanger 24, and this line preferably connects with line 19.

The feed stock for the system passes from the storage tank 26 through line 27 to the accumulator tank 28 and thence through line 29 to the vapor heat exchanger 8 which may be in or adjacent the top of tower 5. Pumps 30 may be arranged, if necessary, in the lines 27 and 29 to forward the oil to the system. The feed stock preheated in the vapor heat exchanger 8 passes through line 31, having a valve 31', into the coil of the tar heat exchanger 24 and thence through lines 32 and 33 into the lower portion of the still 1. Alternatively, the oil may by-pass the tar heat exchanger by being diverted to branch line 34 in which a valve 34' is installed. It will be seen that feed stock free from condensate is introduced into a distillation zone. This is important especially in those cases where it is desirable to keep some or all of the condensate from passing to the cracking zone, for the avoidance of carbon troubles and the like.

The digesting chambers or soaking drums 17, 18 discharge through the line 35 and pressure release valve 36 into the line 37. Valves 38 and 39 are interposed respectively on opposite sides of the inlet to line 37. By proper actuation of these valves the oil may be sent either into the still through branch line 33

or into the bottom of the tower 5 through the main line 37.

The cracking coil 16 may discharge into either or both of the drums 17, 18. These are 5 preferably arranged in parallel, as shown, and are connected with the line from the cracking coil by branch pipes 40, 41 in which valves 42 and 43 are respectively arranged. Branch lines 44 and 45 connect the drums 10 with line 35.

The coil and drums are designed to be operated at relatively high pressure, as is well understood in the art, and the drums should be thermally insulated as by means 15 of a lagging 46, or in some other suitable way. A pressure release valve 36' may be installed in the condenser line 10, for use when the still is operated under pressure, as described further on.

20 The following is an example of the use of the process in treating a low grade stock, such as Smackover crude: Assuming the system to be in operation, a stream of the Smackover crude or the like is passed into the system through lines 27 and 29, is preheated 25 in the vapor heat exchanger 8 and tar heat exchanger 24, and is then passed continuously into the still 1 through lines 32 and 33 at a temperature around 500° F. The pre-heated oil becomes mixed with the cracked stock entering the still from the digesting 30 chambers or soaking drums 17, 18 through lines 35, 37 and 33. Distillation takes place in the still 1 and vapors pass up into the 35 tower 5 for fractionation. Additional heat may be supplied to the still as described below. The bottom of the tower may serve as a hot accumulator for the condensate stock which is to be recycled through the system, 40 or the accumulator 13a may be used. This stock is drawn off through lines 13 and 14 and is passed by the pumps 15 through line 15' to the cracking system. Valves 12, 20, 22, 23', 34', and 38 are closed and valves 45 22', 22'', 31', and 39 are open during this operation. One or both of valves 42 and 43 are open in accordance with whether one or both drums are in use.

The temperature at which oil enters the 50 drum or drums may be about 850° F. The temperature of the product withdrawn from the drum or drums may be about 775° F. Vapors and liquids together are passed into the still through lines 35, 37 and 33.

55 The pressure in the coil and drums may be about 300 to 350 lbs. per sq. in. This pressure may be reduced through the release valve 36 to substantially atmospheric pressure. The cooling incident to expansion of 60 vapors may reduce the temperature of the oil beyond the release valve to about 725° F.

The heat content of this oil is not usually sufficient to distill the crude oil. The proper amount of additional heat is therefore supplied 65 to the still, preferably by passing hot

combustion gases through its internal flues 3. This method of heating is preferred, as it in large measure avoids the coking difficulties in the still which might be encountered if it were attempted to apply external heat. However, some external heat may be applied to the still in the installation shown. All the heat may be supplied externally, if adequate precautions are taken to prevent overheating, for example by using muffle furnaces.

The temperature of the oil in the still may be about 650° F. The still may be operated under pressure, for example 60 lbs. per sq. in. In treating crudes such as Smackover crude, however, the primary purpose of the still is to strip the feed stock, and the distillation is ordinarily best conducted under atmospheric or lower pressure so that the heat requirements may be kept low. Pressure in the still is more desirable when gas oil or the like is being cracked, as will be referred to later.

In starting the operation the still 1 is charged with the feed oil and fired to a distillation temperature. Meanwhile, gas oil or the like is supplied from an external source 90 to the cracking coil, which is suitably fired. The effluent from the coil is discharged into the drum or drums and the cracked product is delivered into the still in the manner described. As soon as the system produces an 95 adequate amount of gas oil, this alone is used as the stock to be cracked. It is collected in the bottom of tower 5 and passes through lines 13, 14, and 15' to the cracking coil.

100 The cracking coil and soaking drums may be operated under any suitable conditions. Generally, the oil will be passed through the coil at such a velocity that most of any carbon forming therein is swept out into the 105 drums. Conversion takes place in the coil and drums in a manner well understood in the art; that is, incipient or partial conversion occurs in the coil and further conversion is effected in the drum, by virtue of the contained heat of the oil.

110 It will be noted that the crude oil itself does not enter the cracking apparatus in this embodiment of the invention. Only the distillate from the crude is cracked. In this 115 way scaling and coking troubles are substantially avoided. The still and tower act as a dehydrating plant, thus obviating the need for supplying separate equipment for this purpose.

120 When operating with feed stock that does not tend to deposit so much carbonaceous matter, such as Panuco crude, in which it is necessary or desirable to crack the crude, the following procedure is adopted: The feed stock is preheated as before by passing through the vapor heat exchanger and the tar heat exchanger and is passed into the still. Heat is suitably applied to the still to distill 125 the feed oil. Vapors are taken off into the 130

tower 5 and the residual oil is drawn from the still through lines 23 and 14 and is conveyed by pump 15 through line 15' to the cracking coil.

6 The cracked product is passed from the drums into the base of the tower 5 through lines 35 and 37. The residuum and condensate collecting in the bottom of tower 5 is drawn off through lines 13, 14, and 21 to the tar heat 10 exchanger, through which it passes in heat interchanging relation with the feed stock entering the system. In running Panuco crude or the like, valves 12, 20, 22', 22'', 34', and 39 are closed and valves 22, 23', 31', and 15 38 are open. An intermediate fraction may be taken off from pan 7 by opening valves 12 and 11" and closing valve 11'. Ordinarily the pan will be allowed to overflow and all condensate will be taken off from the bottom 20 of the tower. The still may be operated under pressure, as described above.

It will be noted that the principal difference between this operation and that described for Smackover crude is that the residuum from the feed oil is cracked and that the cracked product is passed into the tower instead of into the still. Also, the heating fluid supplied to the tar heat exchanger 24 is the hot heavy residuum and condensate 20 tending to accumulate in the bottom of tower 5. This material supplies an amount of heat comparable to that derived from still residuum in the Smackover process described above.

25 When operating with gas oil or the like, the following procedure is preferred: Gas oil is brought in through the vapor heat exchanger 8 and lines 31, 34, 32, and 33 into the still. There is very little residuum formed when gasoil is the stock being treated, and for this reason the tar heat exchanger is not ordinarily used. The still is preferably operated under pressure, for example 60 lbs. per sq. in. as in this way a higher preheat of the gas oil is possible than when working at normal pressure. An additional advantage of pressure is that it permits a forced feed to the pumps 15, thereby preventing possible loss of suction when pumping hot stock.

The gas oil is stripped in the still 1 and the residuum is taken off through lines 23, 14, and 15' to the cracking coil. Vapors pass up into the tower 5 and condensate is collected in the pan 7 for return to the still through line 11. If desired, this condensate may be withdrawn through lines 11 and 11a to storage or passage to the cracking coil. The cracked product from the soaking drums is injected into the tower, as described in connection with the Panuco operation. The heavy residuum with perhaps a small portion of condensate is taken off from the bottom 55 of the tower through lines 13 and 19 to the cooler. This material may be passed through

the tar heat exchanger and utilized to heat the gas oil, if it is desired to secure additional preheat. In this operation (the tar heat exchanger not being used and condensate being returned) valves 11", 22, 22', 22'', 31', and 39 are closed and valves 11', 12, 20, 23', 34', and 38 are open.

70 While the use of digesting drums is preferred, it will be understood that the invention is not limited to any particular equipment for cracking. Various modifications and alternative arrangements may be made within the scope of the appended claims, in which it is our intention to claim all novelty inherent in the invention as broadly as the 80 prior art permits.

We claim:

1. Process of cracking hydrocarbon oil, comprising subjecting a charge of fresh feed oil to a distillation temperature in a distillation zone, fractionating vapors therefrom in a fractionating zone and recovering the distillate, supplying to the distillation zone feed oil unmixed with condensate formed in said fractionating zone, cracking the unvaporized fresh feed oil that has been subjected to distillation, and injecting the hot cracked vaporous and liquid product into the fractionation zone.

85 90 95 100 105 110 115 120 125 130

2. Process of cracking hydrocarbon oil, comprising subjecting the oil to a distillation temperature, fractionating vapors therefrom in a fractionating zone and recovering the distillate, supplying to the distillation zone feed oil free from condensate formed in said fractionation, heating the oil that has been subjected to distillation to a cracking temperature to produce partial cracking therein, digesting the partially cracked oil, and injecting the same into the fractionation zone.

110 115 120 125 130

3. Process of cracking hydrocarbon oil, comprising supplying fresh feed oil to a distillation zone in which it is heated to a distillation temperature, fractionating vapors therefrom in a fractionating zone to produce a distillate product, withdrawing and cracking hot residuum from the distillation zone, delivering the hot cracked product into the base of the fractionating zone, and separately withdrawing liquid residuum and partial condensate from the fractionating zone.

4. Apparatus for cracking hydrocarbon oil, comprising cracking equipment, a still, means for heating the same, means for supplying feed oil to the still, fractionation apparatus connected to the still, means for taking off a light distillate and an intermediate fraction from the fractionation apparatus, a chamber in the lower portion of the fractionation apparatus, means for passing oil from the still to the cracking equipment, and means for delivering products from the cracking equipment either to said still or said chamber.

5. Apparatus for cracking hydrocarbon

oil, comprising cracking equipment, a still, means for heating the same, means for supplying feed oil to the still, fractionation apparatus connected to the still, means for taking off a light distillate and an intermediate fraction from the fractionation apparatus, means for delivering products from the cracking equipment either to said still or said fractionating apparatus, means for withdrawing liquid from the fractionating apparatus, means for returning the intermediate fraction to the still, and means for supplying to the cracking equipment either said intermediate fraction or feed oil from the still.

5 6. Apparatus according to claim 5, comprising a heat exchanger, means for passing feed oil therethrough, and means for passing, in heat interchange with such oil, either liquid oil from said chamber or from said still.

10 7. Process of cracking hydrocarbon oil, comprising supplying the oil to a distillation zone in which it is heated to a distillation temperature, fractionating vapors therefrom in a fractionating zone to produce a distillate product, withdrawing and heating the hot residuum from the distillation zone to a cracking temperature to partially crack 15 the same, digesting the hot partially cracked stock to produce further cracking therein, delivering the hot digested product into the lower portion of the fractionating zone, and separately withdrawing liquid residuum and 20 partial condensate from the fractionating zone.

25 8. Process of cracking hydrocarbon oil, comprising supplying the oil to a distillation zone in which it is heated to a distillation temperature, fractionating vapors therefrom in a fractionating zone to produce a partial condensate and a distillate product, returning such partial condensate to the distillation zone, withdrawing and cracking the hot mixture of residuum from the oil supplied to the distillation zone and the partial condensate, passing the hot cracked product to the fractionating zone, and withdrawing liquid residuum from the fractionating zone.

30 9. Process according to claim 8 in which the withdrawn hot mixture of residuum from the oil supplied to the distillation zone and the partial condensate is first subjected to incipient cracking and then to a digesting 35 operation.
